UNITED STATES PATENT OFFICE

2,629,141

FLOATING INNER PAN FOR REFRIGERATOR
CABINET DOORS

John S. Palmer, Evansville, Ind., assignor to International Harvester Company, a corporation of New Jersey

Application April 11, 1950, Serial No. 155,311

4 Claims. (Cl. 20—35)

1

This invention relates to refrigerating apparatus, but more particularly to the refrigerator cabinet construction and the provision of improved means for slidably supporting the inner panel of the cabinet door.

In the conventional refrigerator cabinet the door is usually fabricated in two parts, i. e., the outer sheet section and the inner panel section. The outer sheet is generally stamped out of a flat metal sheet and is provided with turned over edges to form rearwardly extending top, bottom and side sections which, in turn, are provided with inwardly turned peripheral edges forming flanges upon which the inner panel may be fixedly secured. The space between the inner panel and the outer sheet is generally filled with a low heat-conducting insulation material. In the past both the outer sheet and the inner panel have been fabricated from metal, hence the thermal conductivity characteristics of both sections were substantially identical. Recently, however, it has been the practice to fabricate the inner panel of the door from a low heat-conducting non-metallic material while the outer sheet is fashioned from metal. Because of this dissimilarity of materials and the inherent difference in the coefficient of expansion thereof, this practice created a new problem evolving from the unequal expansion and contraction of these two door sections when fixedly secured to one another. The result of this unequal expansion and contraction frequently causes distortion and twisting of the door which, in turn, disturbs the alignment thereof and, accordingly, makes it difficult to maintain a good seal around the resilient gasket generally provided between the door and the cabinet. Heretofore various means have been proposed to accommodate a limited amount of expansion and contraction in one section of the door without disturbing its associated section, thereby partially compensating for the differences in coefficients of expansion of the materials in the two door sections. Such devices as have been proposed, however, have not been entirely satisfactory and thus the principal object of this invention, therefore, is to provide an improved means for slidably mounting the inner panel in a refrigerator cabinet door.

Another object is to provide an improved means for mounting an inner panel in floating relation with respect to the outer panel in a refrigerator door so as to permit the free expansion and contraction thereof.

A further object is to provide an improved refrigerator cabinet door wherein a non-metallic

2

inner panel is secured in such manner as to permit its free expansion and contraction with respect to the outer panel of said door.

A still further object is to provide a refrigerator cabinet door comprising an outer metallic section and an inner non-metallic section in which the inner panel is free to expand and contract without disturbing the alignment of the door.

10 Another important object is to provide a channel-like member for mounting the inner panel in floating relation to the outer panel of a refrigerator cabinet door.

15 A further object is to provide an improved means for mounting an inner panel in floating relation with respect to the outer panel and to so position such means with respect to the gasket seal that said seal will conceal said mounting means from the view of an observer.

20 The foregoing and other objects and features of the invention will become apparent as the disclosure is more fully met in the following detailed description of a preferred embodiment of the invention as illustrated in the accompanying sheets 25 of drawings in which:

Fig. 1 is a front view of a refrigerator cabinet with parts broken away.

Fig. 2 is a fragmentary view taken along one marginal edge of the inner panel of the closure door.

30 Fig. 3 is an isometric view of a portion of the fastening member embodied in the present invention.

Fig. 4 is a section taken on line 4—4 of Fig. 3.

Fig. 5 is a section taken on line 5—5 of Fig. 1 showing the assembly of the inner panel in the fastening member.

Referring specifically to the drawings, it will be noted that a conventional front-opening type of refrigerator cabinet has been illustrated, but, since the present invention is likewise applicable to other types of refrigerated cabinets, its application should not be limited to the specific embodiment shown. In the drawings, the numeral

40 10 indicates a conventional refrigerator cabinet comprising an inner shell 11 spaced from an outer shell 12 and separated therefrom by suitable insulation material 13 and a closure door 14 hingedly supported by hinges 15 to said outer shell. The outer and inner shells are more or less conventional in construction and are formed with a top, opposite side walls and a bottom, which, for purposes of simplification, have not been shown in great detail or numbered unnecessarily in the drawings. The inner shell 11 en-

compasses a food storage compartment 16 the air in which may be cooled in conventional manner by means of mechanical refrigerating apparatus including a compressor-condenser unit located in the lower rear portion of the cabinet but not shown since the refrigerating apparatus forms no part of the present invention and any of the well-known types may be used. The forward marginal edge of the outer shell 12 may be bent back over itself and then inwardly as indicated at 17 to form a channel having parallel spaced-apart extensions or lips 18 and 19, while the forward marginal edge of the inner shell may be angled over to form an inwardly projecting flange or lip 20. A preformed breaker strip 21, fashioned from a low-heat-conducting plastic or fibrous material of the non-hydroscopic and non-metallic type, is fashioned preferably so as to provide a transversely curved contoured portion proximate one edge thereof. Such member may, if desired, be fabricated in a plurality of sections and then installed end to end around the door opening, but, for the sake of appearance, it is preferred that such member be fashioned so that only one such section is required on each side and one each on the top and bottom of the door opening. The ends of each section of the breaker strip member 21 may, if desired, be mitered or angled as indicated at 22 to improve appearance and facilitate assembly.

A turned-in lip or flange 23, fashioned along one marginal edge, and a lateral extending lip 24 spaced inwardly from the opposite marginal edge of the breaker strip member may provide abutments for purposes which will be more fully explained hereinafter.

The spring clip member, indicated generally by the numeral 25 and fashioned from suitable resilient material, such as spring steel or the like, is provided with an inwardly bent portion proximate one end thereof while the end itself is inwardly turned as indicated at 26, and the opposite end of said member is formed with a flat portion 27 contiguous with a large radius curved portion as shown at 28. Spaced from one end of the clip, on the face opposite the inwardly turned portion 26, there is provided an outwardly projecting extension or lip 29 which, if desired, may readily be fashioned by punching a portion of material out from the clip. This lip, preferably, is located at the point where the end portion 26 joins the flat portion 27. A plurality of such clip members may be employed and it has been found desirable to provide a sufficient number to permit spacing at intervals of approximately six inches throughout the length of each section of the breaker strip member. In assembling a breaker strip of this character, in a refrigerator cabinet, a spring clip 25 is first positioned so that the lip 29 thereon abuts the rib 24 on the breaker strip member, then the opposite or curved end portion 28 of said clip is forced into abutting relation with the lip or flange 23 so that the portion of the clip between the ribbed abutments becomes spring loaded. Additional clips may similarly be placed in position against the individual sections of the breaker strip after which each section may be placed in position between the inner and outer walls of the cabinet. The foregoing breaker strip construction is illustrated only as a preferred embodiment for a refrigerator cabinet of this character, and, since it has been further described in a co-pending application Serial No. 86,103, filed April 7, 1948, now U. S. Patent No. 2,587,922 issued March 4, 1952, entitled "Breaker

Strip Construction," it forms no part of the present invention.

The door 14 comprises an outer shell 30 of dish-like conformation having upwardly extending sides 31 which are bent inwardly at right angles to form a peripherally extending inner wall portion 32, the marginal edges of which are bent inwardly substantially at right angles to form an inwardly turned flange 33 spaced from said side wall 31. The flange and rear wall portion extend peripherally about the rear of the door and provide a supporting member upon which a door gasket seal and an inner panel may be mounted. A resilient door gasket seal 34, having a longitudinally extending opening 35 along one edge thereof that opens into a pocket 36 therein, is positioned against said rear wall portion 32 and secured thereto by any suitable means, such as the self-tapping screws 37 which, in turn, are threaded into openings 38 in said wall portion 32.

A longitudinally extending clip-like fastening member 39, which is fashioned preferably from some suitable material such as spring steel or the like, is formed with a bight section having spaced apart parallel legs 40 and 41 connected by a cross leg 42 at one end thereof, and further provided with an outwardly extending flange member 43 that extends at right angles from one end of the leg 41. A plurality of openings 44 and 45 of different diameters but axially aligned, respectively, in opposed legs 40 and 41 are adapted to cooperate with the screws 37 for fixedly positioning said fastening member. The openings 44 in the leg 40 are large enough to permit the head of the self-tapping screw 37 to pass therethrough without obstruction, while the openings 45 in the leg 41 are somewhat smaller and are adapted to freely accommodate only the shank of said screws. With this arrangement the fastening member 39 may be fixedly secured in position against the inner wall of the pocket 36, of the gasket 34, by the same screws that retain the gasket in position against the rear wall portion 32. Access to the screws may be had through the large openings 44 in the leg 40. In the embodiment illustrated the large openings 44 are shown as being slotted and extending partially into the cross member 42, but it will be understood that the invention is not limited to the specific type of opening shown.

The inner panel section 46, of the door 14, is fashioned preferably from a non-metallic low-heat conducting material that may be contoured as indicated, or otherwise, without departing from the spirit of the invention. Heat insulating material 47 may be disposed between said inner panel and the outer shell 30. The marginal edges 48, of said panel, however, preferably are flat with all of said edges lying in the same horizontal plane, while the thickness of the panel should approximate the distance between the opposite legs in the fastening member 39. Slotted openings 49 along the marginal edges of the panel, and spaced at intervals to correspond with the interval spacing of the openings 44 and 45, in the fastening member 39, are provided for the purpose of facilitating access to the screws 37 after said panel has been positioned.

In the assembly of this door structure the fastening member 39 is usually first slipped over the marginal edge of the inner panel 46 while the gasket seal 34 is positioned around the opening and against the rear wall portion 32 and the holes therein line up with the openings 38 in said wall portion. The inner panel, with the

fastening means thereon, may then be slipped through the slotted openings 35, of the seal 34, and into the pocket 38 therein until the inner face of the extending flange 43 firmly abuts the outer face of the flange member 33 of said rear wall portion. With these members now in position the upward portion of the gasket seal may be turned upwardly out of the way, while the screws 37 are threaded into the aligned openings respectively in the fastening member, the gasket seal and the rear wall portion 32, thus slidably securing the assembly.

Since the spacing of the opposed legs in this member approximates that of the thickness of the inner panel member, it will be appreciated that while the panel will fit snugly therein, it will be free to expand and contract without disturbing the alignment of the outer shell. Furthermore, the spring-like characteristic of the fastening member will serve to firmly retain said inner panel member, thus eliminating rattle, without unduly restricting the movement thereof because of expansion and contraction.

From the above it will be appreciated that the present invention provides a simple and inexpensive, yet effective, means for mounting an inner panel in a refrigerator door in floating relation with respect to the outer panel thereof in order to permit the free expansion and contraction of said panel.

Although only a preferred form of the invention has been shown and described, it will be obvious to those skilled in the art that it is not so limited, but is susceptible of various modifications without departing from the spirit thereof, and it is desired, therefore, that only such limitations shall be placed thereon as are specifically set forth in the appended claims.

What is claimed is:

1. A cabinet door comprising sheet material formed to provide front, top, bottom and side walls, with the top, bottom and side walls each having an inwardly turned rear wall portion and an inwardly turned flange depending therefrom, a resilient gasket secured to said rear wall portions and extending around the rear edge of the door and having a pocket in one side thereof, a fastening member formed with spaced apart and substantially parallel legs with a flange depending from one leg thereof, said fastening member being adapted for positioning in said gasket pocket with the flange of said member positioned so as to overlie in closely abutting relation the depending flange of said rear wall portions, means for securing said fastening member and said gasket to said rear wall portions, a panel forming the inner side of said door and extending between said rear wall portions with the marginal edges thereof extending into said fastening member and into frictional engagement with the spaced apart legs of said member whereby said member securely holds said panel in floating relation with respect to said walls.

2. A cabinet door comprising sheet material formed to provide front, top, bottom and side walls with the top, bottom and side walls each having an inwardly turned rear wall portion and an inwardly turned flange depending therefrom, a resilient gasket secured to said rear wall portions and extending around the rear edge of the door, said gasket having a longitudinally extending pocket opening in one side thereof, a resilient clamping member having spaced apart and substantially parallel side wall portions with a flange depending from the end of one of said side

wall portions, said clamping member being positioned in said gasket pocket so that one face of the flange thereof abuts one face of the depending flange of said rear wall portions, means for securing said clamping member and said gasket to said rear wall portions so that a portion of said gasket is disposed between said clamping member and said rear wall portions, a panel forming the inner side of said door and extending between said rear wall portions with the marginal edges of said panel extending into said clamping member and into frictional engagement with the spaced apart wall portions of said member whereby said member securely holds said panel in floating relation with respect to the said rear wall portions.

3. A cabinet door comprising sheet material formed to provide front, top, bottom and side walls, with the top, bottom and side walls each having an inwardly turned rear wall portion and an inwardly turned flange depending from the marginal edge thereof, a resilient gasket secured to said rear wall portions and extending around the rear edge of the door and having a pocket in one side thereof, an independent fastening member formed with spaced apart and substantially parallel legs with a flange depending from one leg thereof, said fastening member being adapted for positioning a portion thereof into said gasket pocket and being further arranged so that one face of the flange thereof overlies and abuts one face of the depending flange of said rear wall portions, means for securing said fastening member and said gasket to said rear wall portions, a panel forming the inner side of said door and extending between said rear wall portions with the marginal edges thereof extending into said fastening member and into frictional engagement with the spaced apart leg portions of said member whereby said member securely holds said panel in floating relation with respect to said walls.

4. A cabinet door comprising sheet material fashioned to provide front, top, bottom and side walls, with the top, bottom and side walls each having an inwardly turned rear wall portion and a coextensive inwardly turned flange depending therefrom, a resilient gasket disposed so that substantially the entire seating surface thereof is positioned on that portion of each of said inwardly turned rear wall portions that extends between said inwardly turned flange and the respective top, bottom and side walls, said gasket extending around the rear edge of the door and being provided with a pocket opening into one side thereof, a longitudinally extending fastening member having spaced apart and substantially parallel leg portions with an integrally fashioned flange depending from the end of one of said leg portions, said fastening member being provided with a plurality of longitudinally spaced openings axially aligned in the opposite leg portions thereof, said fastening member being positioned in said gasket pocket and further arranged so that one face of the depending flange thereon overlies and abuts in contacting relation one face of the depending flange of said rear wall portions, means including self-tapping screws for securing said fastening member and said gasket to said rear wall portions, and screws being selected so that the head of each will pass through an opening in one leg of the fastening member but only the shank thereof will pass through an aligned opening in the opposite leg of said member, a non-metallic panel having a plurality of slotted openings disposed at intervals around the

peripheral edges thereof, said panel forming the inner side of the door and disposed so as to extend between said rear wall portions with the marginal edges of the panel extending into said fastening member and into frictional engagement with the spaced-apart leg portions of said member while the slotted openings in the panel co-operate with the openings in one leg of said fastening member to provide access to said screw securing means thereby securely holding said panel in floating relation with respect to said walls and without interfering with said securing means.

JOHN S. PALMER.
